UNITED STATES PATENT OFFICE.

HENRY KERSHAW, OF CHICAGO, ILLINOIS.

FILTER.

1,247,118.

Specification of Letters Patent. Patented Nov. 20, 1917.

Application filed August 24, 1917. Serial No. 187,991.

To all whom it may concern:

Be it known that I, HENRY KERSHAW, a citizen of the United States, residing at Chicago, in the county of Cook and State 5 of Illinois, have invented new and useful Improvements in Filters, of which the following is a specification.

The filter which is the subject matter of the present application for patent is de- 10 signed more particularly for use in connection with motorcycles and cars for the purpose of assuring a clean supply of gasolene to the carbureter, the filter being interposed in the pipe line leading from the gasolene 15 supply tank to the carbureter.

The invention has for its object to pro- 20 vide a simple and efficient filter of the kind stated, which can be readily installed, and which is so constructed that it can be easily

taken apart for cleaning, repairs, etc.

With the object stated in view, the invention consists in a novel combination and ar- 25 range ment of parts to be hereinafter de- scribed and claimed, and in order that the same may be better understood reference is had to the accompanying drawing, forming a part of this specification.

In the drawing,

Figure 1 is a perspective view of the 30 filter;

Fig. 2 is a central vertical section thereof; and Figs. 3 and 4 are cross sections on the lines 3—3 and 4—4, respectively, of Fig. 2.

Referring specifically to the drawing, 5 de- 35 notes a filtering vessel in the form of an up- right cylinder having a closed bottom 6 and a top closure 7, the latter being a screw cap. The cap 7 does not seat directly over the top of the vessel 5, but is detachably connected 40 to a neck 8 carried by the latter. This neck is a ring having top and bottom reduced portions which are screw-threaded, the for- mer receiving the cap, and the latter being screwed into the top of the vessel, the parts 45 being thus all separably connected.

The bottom 6 of the vessel 5 is provided with an inlet nipple 9 for connection to the gasolene line, and it is also fitted with a drain cock 10.

50 In the vessel 5 is mounted and fitted snugly therein, a glass cylinder 11, the side of the vessel has an opening 12 exposing said cylinder and forming a sight opening through which the fluid level in the vessel 55 may be observed. The glass cylinder seats

on the bottom of the vessel and it is held in the vessel by the neck 8, the bottom edge of the latter having an inturned marginal flange 13 seating on the top edge of the cylinder. Thus the glass cylinder is firmly 60 held when the neck 8 is screwed down on the vessel. Between the top edge of the neck 8 and the under side of the cap 7 is interposed a gasket 14. The outer surface of the cap is formed square to permit ap- 65 plication of a wrench or other tool for putting on or taking off the cap.

In the neck 8 snugly fits a sleeve 15 the same resting on the flange 13 and being kept from turning in the neck by a cross bar or 70 pin 16 which projects at its ends from the outer periphery of the sleeve to seat in vertical grooves 17 in the wall of the neck on the inside thereof.

In the sleeve 15 are mounted two strainer 75 disks 18 of fine gauze, with a thick felt pad 19 therebetween.

Above the top strainer disk 18, the sleeve 15 has a side aperture 20 registering with an outlet nipple 21 on the neck 8, to which 80 nipple is connected a piping which leads to the carbureter. As the cross bar 16 pre- vents the sleeve 15 from rotating, the aper- ture 20 remains in line with the nipple 21.

The gasolene line from the supply tank 85 (not shown) is connected to the inlet nipple 9, and said tank being positioned above the level of the vessel 5, the gasolene will flow into the vessel by gravity. Before the gasolene is turned on, the vessel 5 is partly 90 filled with water. Now when the gasolene is turned on it flows into the vessel and bubbles up through the water therein, filling the upper portion of the vessel and passing through the strainer disks 18 and pad 19, 95 and thence escaping through the outlet 20, to be carried to the carbureter. By its pas- sage through the water the gasolene will be relieved of heavy dirt particles, and a fur- ther straining action takes place when the 100 gasolene passes through the strainer ele- ments 18 and 19, the latter intercepting and holding any water which may be present in the gasolene, and thereby assuring isolation

of water if the two liquids should be agi- 105 tated by excessive jar so as to splash the water to the strainer elements. The sediment collecting in the bottom of the vessel can be run out by opening the drain cock 10. The entire apparatus can also be 110

cleaned out by removing the sleeve 15, which can be readily done after taking the cap 7 off.

I claim:

1. A filter comprising a vessel having a bottom inlet and adapted to hold a wash liquid, and having an outlet above the liquid level, a neck attached to the top of the vessel and having an internal flange, a sleeve in the neck and seating on the flange, a cap closing the neck and engaging the sleeve to hold the same seated on the flange, and a screen carried by the sleeve, said screen being located between the top of the liquid and the outlet of the vessel.
- 15 2. A filter comprising a vessel having a bottom inlet and adapted to hold a wash liquid, and having an outlet above the liquid level, a neck attached to the top of the vessel and having an internal flange, a sleeve in the neck and seating on the flange, a cap closing the neck and engaging the sleeve to hold the same seated on the flange, a screen carried by the sleeve, said screen being located between the top of the liquid and the outlet of the vessel.
- 20

cated between the top of the liquid and the outlet of the vessel, the sleeve having an escape aperture in alinement with the outlet, and means for locking the sleeve against rotation.

3. A filter comprising a vessel having a bottom inlet and adapted to hold a wash liquid, and having an outlet above the liquid level, a neck attached to the top of the vessel and having an internal flange, a sleeve in the neck and seating on the flange, a cap closing the neck and engaging the sleeve to hold the same seated on the flange, a screen carried by the sleeve, said screen being located between the top of the liquid and the outlet of the vessel, the sleeve having an escape aperture in alinement with the outlet, and pins projecting from the side of the sleeve, the interior of the neck having grooves in which the pins seat to hold the sleeve against rotary movement.

In testimony whereof I affix my signature. 45
HENRY KERSHAW.
